UNITED STATES PATENT OFFICE.

ALONZO F. SMITH, OF BOGARD, MISSOURI.

DESIGN FOR A REIN-HOLDER.

SPECIFICATION forming part of Design No. 33,337, dated October 9, 1900.

Application filed September 1, 1900. Serial No. 28,850. Term of patent 7 years.

To all whom it may concern:

Be it known that I, ALONZO F. SMITH, a citizen of the United States, residing at Bogard, in the county of Carroll and State of Missouri, have produced a new and original 5 Design for a Rein-Holder, of which the following is a specification.

This invention relates to a design for a rein-holder; and the leading feature consists 10 in the design as disclosed by the accompanying illustration, wherein—

Figure 1 is a perspective view of a rein-holder embodying the features of the design. Fig. 2 is a side elevation of the same.

15 The design is characterized by divergent legs 1, having terminal-looped ends 2 and emanating from an upper body-stem 3, continuing into an upstanding transversely-extending loop 4 of rectangular form. From

the center of the upper portion of the said 20 rectangular loop 4 an upwardly-inclined support 5 extends and is also provided with an upstanding rectangular terminal loop 6. Depending from the said support is a member 7, having an upper curved extremity 8 and 25 a lower flattened end 9.

Having thus described the invention, what is claimed as new is—

The design for a rein-holder, herein shown and described. 30

In testimony that I claim the foregoing as my own I have hereto affixed my signature in the presence of two witnesses.

ALONZO F. SMITH.
